UNITED STATES PATENT OFFICE.

GEORGE H. ALLEN, OF NORTH CREEK, NEW YORK.

STRIPING DEVICE.

SPECIFICATION forming part of Letters Patent No. 660,881, dated October 30, 1900.

Application filed April 19, 1900. Serial No. 13,484. (No model.)

To all whom it may concern:

Be it known that I, GEORGE H. ALLEN, a citizen of the United States, and a resident of North Creek, in the county of Warren and State of New York, have invented new and useful Improvements in Striping Devices, of which the following is a full, clear, and exact description.

This invention has for its object to provide a novel, simple, and practical device which will afford means by its manipulation to accurately produce stripes on flat or rounded surfaces with liquid paint or other suitable material.

The invention consists in the novel construction and combination of parts, as is hereinafter described, and defined in the appended claims.

Reference is to be had to the accompanying drawings, forming a part of this specification, in which similar characters of reference indicate corresponding parts in all the figures.

Figure 1 is a perspective view of the complete device. Fig. 2 is a sectional side view of the same, taken substantially on the line 2 2 in Fig. 3. Fig. 3 is an upper end view of the striper, and Fig. 4 is a side view of the lower portion of the instrument seen in the direction of the arrow x in Fig. 3.

In carrying into effect the features of the invention as illustrated in the drawings, 5 indicates the liquid-holding reservoir of the device, which is also the handle whereby the instrument is manipulated in use. The reservoir 5 is preferably made in hollow cylindrical form, having a suitable length for effective service, and upon the normal upper end thereof a cap-piece 6 is removably secured in a liquid-tight manner. As shown, the cap-piece 6 has a threaded engagement within the threaded interior of the upper end of the reservoir. A vent-orifice a is formed in the head wall of the cap-piece 6 and is closed by the adjustable gate 7, which permits a graduation 45 of the size of the vent-hole a.

The lower end of the reservoir-wall 5 is internally threaded to receive the externally threaded upper end of a cylindrical extension-piece 5^a, provided for said reservoir. The lower end portion of the extension-piece 5^a is contracted, so as to provide an integral end wall b thereon, which is longitudinally and

centrally perforated for the reception of one end of the nozzle-tube 8.

The nozzle-tube 8 has a screwed engagement with the perforation in the end wall b, and it may here be explained that a plurality of nozzle-tubes may be provided which have different diameters in their bores, so that by an exchange of nozzle-tubes the device may be adapted for the execution of stripes having different widths, in a manner which will be hereinafter described.

In the extension-piece 5^a a plug 9 is fitted closely and secured, which plug preferably 65 is extended from the end wall b to the upper end of the extension-piece, as shown in Fig. 2. There is a comparatively small-dia-metered perforation c formed axially in the plug 9 and is alined with the bore c' of the nozzle-tube 8, as shown in Fig. 2.

Upon the body of the reservoir 5 a clip-band 10 is mounted somewhat above the end wall b of the extension-piece 5^a, and in the ears 10^a formed on the clip-band opposite perforations are formed to receive the clamping-bolt d, as best shown in Fig. 3.

A guide-arm 11 is provided as an essential feature of the striping device, and consists of a flat strip of rigid material, preferably 80 bent edgewise near one end, as at e in Figs. 1 and 2, thus producing a laterally-bent finger 11^a at one end of said arm.

The guide-arm 11 is widened toward its opposite end, which end is introduced between 85 the ears 10^a and pivoted upon the bolt d, which bolt is so adjusted that the arm may be moved as required, but will not be liable to change its adjustment accidentally.

Between the clip-band 10 and nozzle-tube 8 90 a ferrule 12, or, if preferred, another clip-band is secured upon the reservoir-body. From the lower portion of the ferrule 12 a preferably spring-limb 13 is projected downward and outward and at the outer end 95 thereof is suitably bent to adapt it for a secured engagement with the side of the rockable arm 14.

The arm 14 is a straight bar having fixed engagement with the spring-limb 13 intermediate of the ends of said arm, and from the set of the spring-limb the lower end of the arm is normally pressed toward the free lower end of the nozzle-tube 8, as clearly shown in

Figs. 1 and 4. Upon the lower end of the arm 14 a cup 15 is formed or secured, which opens in the direction of the lower end of the nozzle-tube 8, and said cup contains leather or other fibrous slightly - yielding material, which, from the trend of the arm and cup thereon, is forced by the spring - limb 13 against the open end of the nozzle-tube, and thus normally closes said end.

10 It will be seen that a suitable degree of pressure applied to the outer side of the arm 14 at its upper end will serve to rock this end of the arm toward the ferrule which supports it, the yielding of the spring-limb 13 permitting such a rocking movement. The inward movement of the upper end of the rockable arm 14 causes a corresponding outward movement of the lower portion of said arm, which will remove the sealing-cup 15 from the end 20 of the nozzle-tube 8, as indicated by dotted lines in Fig. 4.

As represented in Figs. 1 and 3, the guide-arm 11 and rockable arm 14 are spaced from each other about ninety degrees, which will 25 locate the guide-arm at the left side of the instrument when it is in service and the other arm 14 on the upper side of the instrument, thus disposing the upper end of the arm 14 in convenient position for finger-pressure when 30 the device is taken hold of by the user.

To adapt the device for use in any necessary adjustment of the guide-arm 11 with regard to the arm 14, it is essential that the guide-arm be adjustably secured on the reservoir 5, so that it may be rotatively moved more or less thereon and readily secured at a proper point of adjustment. To this end I have provided the clip - band 10, that is clamped in a desired position by the bolt *d*, 35 that serves as a pivot-support for the guide-arm.

It will be seen that if the improved instrument is charged with a quantity of liquid paint the operator may by opening the lower 45 end of the nozzle-tube permit a minute stream of paint to flow slowly from the tube.

To stripe a surface with one or more straight lines, the guide-arm 11 is adjusted so that the finger end thereon may engage with a 50 straight edge that is either upon the article to be striped or held applied thereto, so that the movement of the instrument progress-

ively along the straight edge, while the open nozzle-tube is held upon the surface to be striped will effect the production of a stripe 55 on the article of a width determined by the bore of the nozzle-tube.

Evidently the surface to be striped may be flat, convex, or concave, as so long as there is a guiding edge afforded for a sliding engagement of the arm 11 a stripe may be formed thereon, which will be controlled in its formation by the shape of the edge with which the guide-arm has contact.

Having thus described my invention, I 65 claim as new and desire to secure by Letters Patent—

1. In a striping device, the combination with a reservoir, a cap-piece screwing on one end of the reservoir having a vent-hole therein, and an adjustable gate controlling the vent-hole, of a nozzle on the opposite end of the reservoir, a flat spring held by one end on said reservoir and extending in direction of the nozzle, an arm supported by the plate-spring so as to be adapted for rocking movement, and a sealing-cup on the lower end of the spring-supported arm which normally closes the discharging end of the nozzle. 75

2. In a striping device, the combination with a reservoir, a screw-cap on one end thereof, and means to control an opening in said cap, of a nozzle on the opposite end of the reservoir, and a spring-supported rockable sealing device on the reservoir adapted to 85 normally close the discharge end of the nozzle and be retracted therefrom by manipulation.

3. In a device of the described construction, the combination with the striping device, of a guide-arm to control the direction of movement of the striping device, and a clip-band having ears adjustably clamped on the striping device, and a pivot-bolt for supporting the guide-arm between the ears of 95 said clip-band, and clamping said band in place.

In testimony whereof I have signed my name to this specification in the presence of two subscribing witnesses.

GEORGE H. ALLEN.
